PNEUMATIC VEHICLE IMPACT BUMPER

Wilbur L. Hiatt, 4508 Commonwealth Drive, Williamsburg Apt. N., Indianapolis, Ind. 46220

Filed May 6, 1971, Ser. No. 141,079

Term of patent 14 years

Int. Cl. D12—16

U.S. Cl. D14—6

Fig. 1.

Fig. 2.

Fig. 3.

Fig. 4.

FIG. 1 is a front elevation of the pneumatic vehicle impact bumper of the present invention.

FIG. 2 is a rear elevation of the structure of FIG. 1.

FIG. 3 is a top plan view of the structure of FIGS. 1 and 2.

The surface texture is shown fragmentarily for convenience of illustration only.

FIG. 4 is a side elevation of the structure of FIGS. 1, 2 and 3.

The bottom plan view of the structure is the same as FIG. 3.

The side of the structure opposite to the side illustrated in FIG. 4 is the mirror image of FIG. 4.

I claim:

The ornamental design for a pneumatic vehicle impact bumper, as shown and described.
